UNITED STATES PATENT OFFICE.

HARRY F. WOERNLEY, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

COUPLER ADAPTER.

Application filed July 2, 1926. Serial No. 120,095.

This invention relates to car couplers, and the principal object of my invention is to provide an adapter by which a car coupler of one type may be coupled to a car coupler 5 of another type.

In the accompanying drawing, the single figure is a plan view, partly in section, of a car coupler with my adapter applied thereto.

The adapter is designed more particularly 10 for application to a tight lock coupler of the type covered by Patent No. 887,296 of George Westinghouse, dated May 12, 1908, and such that the tight lock coupler may be coupled to a coupler of the link and pin 15 type.

The tight lock coupler comprises a casting 1, having a projecting portion 2 and a recess 3 for engaging corresponding parts of a counterpart coupler head on an adjacent car.

20 The coupler head is provided with a pivoted latch or locking lever 4 having a cam face for engaging a face 5 on the projecting portion 2 of a counterpart coupler head for locking the heads in engagement.

25 The adapter may comprise a casting 6 having a projecting portion 2', similar to the projecting portion 2 of the tight lock coupler head and a recess 3', and the projecting portion 2' is provided with a face 5' adapted 30 to be engaged by the cam face of the locking lever 4 of the tight lock coupler head.

Instead of the pivoted locking lever, the adapter is provided with a movable block 7, mounted in a recess 8 in the adapter, and 35 having an elongated slot 9 in which a pin 10, secured to the adapter, is mounted. A face 11 of said block is adapted to engage the face 5 of the tight lock coupler head, and adapted to engage the opposite parallel face 12 is a 40 screw 13, having a screw-threaded engagement in the casting 6. The screw 13 may be provided with a pivotally connected operating handle 14.

A coupler head of the link and pin type 45 is shown connected to the adapter and comprises a casting 15 having a transverse face 16 adapted to engage the corresponding face of a counterpart coupler head and having a cavity 17 into which the connecting link 50 (not shown) projects. Said link is held in the coupler head by a coupling pin 18. To

take the place of the link, the adapter is provided with a projecting tongue 19 having an opening adapted to receive the coupling pin 18.

55 In order to apply the adapter to a tight lock coupler head, the screw 13 is backed off and the block 7 is moved outwardly. The adapter is then applied, so that the locking lever 4 of the tight lock coupler engages the 60 face 5' of the adapter. The block 7 is then moved inwardly to the position shown in the drawing and the screw 13 is operated to clamp the block 7 against the face 5 of the tight lock coupler head. The adapter is 65 thus firmly secured to the coupler head.

In coupling with a link and pin coupler, the tight lock coupler head with the adapter attached is brought into engagement with the link and pin coupler, so that the face 16 70 engages a corresponding face of the adapter. The tongue 19 then engages in the recess 17 and the locking pin 18 is dropped into place, as shown in the drawing, thus coupling the 75 adapter to the link and pin coupler head.

If the screw 13 should work loose while the couplers are coupled together, the face 16 of the link and pin coupler head will prevent the block 7 from working free of engagement with the face 5, so that unlocking 80 of the parts is prevented.

Having now described my invention, what I claim as new and desire to secure by Letters Patent, is:

1. The combination with a tight lock coupler head having a projecting portion provided with a clamping face and a locking lever having a cam face adapted to engage the clamping face of a cooperating coupler head, of an adapter adapted to couple with said tight lock coupler head and having means for coupling with a coupler head of another type and provided with a movable block having a face adapted to engage the clamping face of the tight lock coupler head, and a manually operable screw for clamping said block into engagement with said clamping face.

2. The combination with a tight lock coupler head having a projecting portion provided with a clamping face and a locking lever having a cam face adapted to engage

the clamping face of a cooperating coupler head, of an adapter adapted to couple with said tight lock coupler head and having means for coupling with a coupler head of another type and provided with a movable block having a face adapted to engage the clamping face of the tight lock coupler head,

a pin secured to said adapter and extending through a slot in said block, and a manually adjustable screw for clamping said block into engagement with said clamping face.

In testimony whereof I have hereunto set my hand.

HARRY F. WOERNLEY.
